TAPE REEL

Charles L. Alden, White Bear Lake, Minn., assignor to
Minnesota Mining and Manufacturing Company, St.
Paul, Minn., a corporation of Delaware

Filed Feb. 3, 1964, Ser. No. 78,492

Term of patent 14 years

(Cl. D61—1)

FIG. 1

FIG. 3

FIG. 2

FIGURE 1 is an elevational view of one side of a tape reel showing my new design;

FIGURE 2 is an elevational view of the other side of a tape reel showing my new design; and

FIGURE 3 is an enlarged end view thereof, partially in section as indicated by line 3-3 on FIGURE 2.

The essential features of my design are shown in full lines in the drawing.

I claim:

The ornamental design for a tape reel, as shown and described.
